UNITED STATES PATENT OFFICE

HOKE SMITH WYNNE, OF EASTMAN, GEORGIA

ADVERTISING EGG TESTER

Application filed February 27, 1931. Serial No. 518,855.

This invention relates to a combined advertising device and egg tester, the general object of the invention being to provide a casing containing a lamp and having a cover part 5 containing an opening so that an egg can be placed over the opening and be tested in the usual manner, the casing also having a sloping part having its top open and provided with means for holding a transparent member over the opening so that the rays of light from the lamp will pass through the transparent member and illuminate advertising matter or the like on said member.

This invention also consists in certain other 15 features of construction and in the combination and arrangement of the several parts, to be hereinafter fully described, illustrated in the accompanying drawings and specifically pointed out in the appended claim.

20 In describing the invention in detail, reference will be had to the accompanying drawings wherein like characters denote like or corresponding parts throughout the several views, and in which:—

25 Figure 1 is a top plan view of the device.
Figure 2 is a section on line 2—2 of Figure 1.

Figure 3 is a front view of the device.

30 Figure 4 is a transverse sectional view through the egg tester, cut on the line 4—4 of Figure 2.

Figure 5 is a similar view, cut on the line 5—5 of Figure 1.

35 In these views, the letter A indicates a casing which is formed with a substantially rectangular rear part and a substantially triangular front part, the front part having its top sloping from the front end of the rectangular part to the front end of the bottom 40 of the casing. A cover 1 is bolted or otherwise detachably connected to flanges 2 which extend inwardly from the upper edges of the rectangular part and this cover member has 45 an opening 3 therein having rounded walls and adapted to receive an egg so that eggs can be tested through means of the rays of light passing therethrough from the lamp 4 in the rectangular part of the casing. A 50 transparent member 5 covers the sloping part

of the front of the casing and contains advertising matter.

Mirrors or reflecting members 6 are placed on the bottom and rear part of the casing for reflecting the rays of light from the lamp 55 through the transparent member 5, the mirror at the rear of the part being diagonally arranged and being held in place by a clip 7 formed by cutting the rear flange 2 and bent downwardly into engagement with the upper 60 end of the mirror. Thus when this device is placed on a counter or the like and a poultryman brings his eggs to a store or the like, the eggs are placed at the opening 3 while being tested and thus as the poultryman watches the 65 testing of his eggs, he will observe the advertising matter on the transparent member. Of course, other persons will see this advertising matter so that the article or matter advertised thereon will be brought to the attention of the observers.

It is thought from the foregoing description that the advantages and novel features of the invention will be readily apparent.

It is to be understood that changes may 75 be made in the construction and in the combination and arrangement of the several parts, provided that such changes fall within the scope of the appended claim.

What I claim is:—

80 A device of the class described comprising a casing having its rear part of substantially rectangular shape and its forward part provided with a downwardly and forwardly sloping top part, the top of the rectangular 85 part having an opening, a transparent member containing advertising matter covering said sloping part, a lamp in the casing and reflecting members in the casing for reflecting the rays of light from the lamp through 90 the opening and through the transparent member.

95 In testimony whereof I affix my signature.

HOKE SMITH WYNNE.
